Application April 26, 1950, Serial No. 158,102

8 Claims. (Cl. 214—18)

1

This invention relates to apparatus for removing drum covers. In one aspect the invention relates to apparatus for removing coking-drum covers. In another aspect the invention relates to apparatus for removing bottom covers of coking drums, employed in delayed coking plants, as more fully hereinafter described, for the purpose of dropping solid coke into freight cars stationed beneath these drums.

Batch-type coking plants are usually comprised of a furnace for heating the viscous fluid bottoms product of oil fractionating towers or stills to a temperature of about 935° F. and a coking-drum for storing the hot bottoms oil fraction for a period of approximately 24 hours until the oil solidifies into coke. The coking-drum is a large structure, generally about 18 feet in diameter and about 90 feet high and is supported about 23 feet above grade on heavy concrete or structural steel framework. The drums are usually arranged in a row of two or more over a railroad track. After the coke has solidified within the drum, it is necessary to quench the hot coke by introducing sufficient water into the drum. The quantity of water thus introduced into the drum is based upon the pump capacity and the period of time required for obtaining a complete quench. Usually the quantity of water required is as high as 4,000 gallons. Water thus introduced into the drum is, in theory, supposed to drain out of the drum after quenching. However, a large portion of the water is trapped within the drum because of clogging of the drains by the solidified coke. The upper cover-plate of the drum is usually removed and a hole approximately 30 inches in diameter is drilled into the upper surface of the coke, within the drum, to the lower cover-plate on the bottom of the drum. The lower cover-plate is then removed, and accumulated water and loose chunks of coke are allowed to drop out of the lower manway. After the loose material has been cleared, a freight car is brought in under the drum and a scraping tool is applied to the coke through the drill hole to break up the coke and push it into the freight car beneath the drum. The lower cover of the above-mentioned coke-drum is usually a steel plate, approximately 82 inches in diameter, 4½ inches in thickness and may weigh as much as 3½ tons. This lower cover is attached to the bottom of the drum by bolts which pass through threaded nuts welded to the periphery of the lower manway.

The formation of solid coke above the lower cover tends to cause it to stick in position. Since

2

there is an unknown amount of water and loose coke material within the drum, which exert a downward force on the cover, it is impossible to ascertain at exactly what point the cover will give way when partially or completely unbolted for the purpose of coke removal. For this reason, it has been the practice, for personnel protection, to place a jack under the cover to retain the mass of water and loose coke in the drum until all the bolts are removed. After the cover has been unbolted, it must be lowered. This is usually followed by a deluge of several tons of water and loose coke. Moreover, the cover often remains stuck in position even after removal of all the bolts, and the problem of jacking it loose is then presented in which personnel must work under dangerous conditions. The resulting debris, the jack, its supporting scaffold and other tools must then be removed before a freight car can be moved in under the lower manway. This troublesome and dangerous operation of the plant depends upon the rotation of service periods of each of the several drums.

It is, therefore, an object of the present invention to provide an apparatus for removing lower covers of coking vessels, for transfer of solid coke without hazard to the operator.

Another object of the invention is to provide an apparatus for removing lower covers of coking vessels, for transfer of solid coke, efficiently and economically.

Other objects and advantages inherent in the invention will become apparent from the following description.

For a complete understanding of the invention reference is had to the following description and drawings in which

Fig. 1 is a transverse section of the lower portion of a coking-drum, in which the apparatus of the present invention is in position for removing the lower cover of the drum;

Fig. 2 is a view of the same apparatus moved aside from the lower opening of the coke-drum while discharge of the contents of the coke-drum into a freight car takes place;

Fig. 3 is a longitudinal side view of the lower portion of the coking plant showing the cover-removing apparatus in position for transfer from one drum to another;

Fig. 4 is a perspective view, partly in section, showing a movable platform and apparatus for removing the lower cover of the coke-drum;

Fig. 5 is an elevational view of a movable wrench employed for loosening or tightening the holding bolts of the lower cover; and

Fig. 6 is a sectional view showing retractable supports for the platform of Fig. 4.

In the following description the term "longitudinal" refers to a direction parallel with the center lines of all the coke-drums, and the term "transversely" refers to a direction which is at right angles to the center lines of all the drums.

As illustrated by the above drawings, the apparatus of the present invention comprises a device for removing the lower cover from the coke drum without endangering personnel and without interfering with freight-car movement under the drum. The apparatus comprises a bolt-removing wrench movably mounted upon a circular track with a device to raise the wrench vertically to engage bolt heads, a hydraulic jack mounted concentrically with the track to support the cover during removal operations (these devices being mounted upon a platform which is movable by trolley beams and a craneway to a cover-removing position), and hydraulic means for operating the jack mounted on the platform in a shielded position in full visual control.

The operation of a coking plant employing the apparatus of the present invention, is shown in Figs. 1, 2 and 3 of the drawings. In these figures the unloading of drums 10 (Figs. 1 and 2) or 11 (Fig. 3) are exactly similar in operation and are carried out with the same apparatus of the invention but at different times. Drums 10 and 11 are two massive cylindrical coke-drums, supported with their vertical axes on a concrete supporting structure 12. The upper portions of drums 10 and 11 and the openings at their upper ends are not shown, since they are not pertinent to the invention herein described.

As indicated above, unloading of drums 10 or 11 are exactly similar operations but are carried out at different times. The unloading devices are supported on a platform 13 which is movable from one drum to the other on rollers 19 by means of transverse trolley beams 15 and a craneway 16. The coke material is removed through a circular flanged opening 17, as shown in Fig. 2, in the lower cone-shaped end 18 of drum 10, by removing a lower cover 20. Cover 20 is attached to opening 17 by means of bolts 21 which pass upwardly through peripheral holes 22, as shown in Fig. 5, in cover 20 and through matching peripheral holes 23 in an annular flange 24, surrounding lower opening 17, so as to thread into nuts 25 above flange 24. When lower cover 20 is removed from drum 10, platform 13 is rolled from the position in which it appears in Fig. 1 to the position in which it appears in Fig. 2, so that coke 26 can be discharged, after being loosened as previously described, into freight-car 27. The movable beams 15, from which platform 13 is suspended are themselves movably suspended by means of rollers 29 to move longitudinally on craneway 16 as seen in Fig. 3.

After platform 13 has been placed in position under drum 10, retractable supports, indicated generally by the numeral 31 and shown in more detail in Fig. 6, are lowered so that the platform is supported on supports 31 and not on trolley beams 14, while lower cover 20 is being removed or replaced. When these supports are lowered platform 13 is actually lifted a short distance, usually about an inch or more.

Each retractable support 31, as shown in Fig. 6, is comprised of a threaded shaft 32 rotatable within a threaded block 33 mounted in a corner of platform 13. Rotation is accomplished by the operator by rotating wheel 34. When platform

13 is newly moved into position under one of the drums, the retractable support will be in an elevated position. When in proper position under the drum, bolts 35 and 37 will be found in position held by washers and nuts 41 in holes 38 in I-beam 39, which runs longitudinally along a shelf 40, as shown in Fig. 1, which comprises part of concrete structure 12. Wheel 34 is rotated to bring the lower end of shaft 32 to bear upon I-beam 39 through a threaded hole in plate 42, and rotation is continued until brought to a stop by the engagement of plate 42 with the heads 43 of bolts 35 and 37. In Fig. 4 is shown plate 42 horizontally positioned under platform 13 and having a center-threaded hole for shaft 32 and loose-fit holes for bolts 35 and 37.

On platform 13, a heavy circular track 50, as shown in Fig. 4, is provided to support a dolly. As shown in Fig. 5, dolly 51 carries a pneumatic wrench 52, supplied with air through lines 53 and movable vertically into position by means of lever arm 54. Lever arm 54 is shown in Fig. 5 in heavy lines in a raised position and in dashed lines 55 in lowered position. Before bolts 21 are actually removed, hydraulic jack 60, as shown in Fig. 4, is raised into position and platen 61 is pushed directly against the lower surface of cover 20. Platen 61 is provided with four vertical lugs 62 (see Fig. 4) projecting radially outward and engageable with corresponding lugs 63 at cover 20. Lugs 62 and 63 are bolted together by means of bolts 64 so that cover 20 can be pulled down by hydraulic jack 60. Rigidity for hydraulic jack 60 is provided at its four corners by four guided columns 65.

Hydraulic jack 60, as shown in Fig. 4, can be operated by means of hand-pump 66 and controls 67, located in a safe position near one end of platform 13 and separated by a shield 70 so as to protect the operator. Window 71 is provided so that the operator may observe the lowering of cover 20 from a safe position behind shield 70, after bolts 21 have been removed with pneumatic wrench 52.

In carrying out the removal of coke employing the apparatus of the present invention, after coke-drum 10 has been closed and made ready for charging, movable platform 13 is moved transversely by pulling at a hand-chain 72, as shown in Fig. 1, connected by suitable gearing to rollers 19. The transverse movement is continued until platform 13 has been moved from the fixed transverse trolley beams 14 onto the movable transverse beams 15, which are suspended from the craneway 16 outside of the structure proper. Craneway 16 is positioned so that the ends of fixed transverse trolley beams 14 and movable transverse beams 15 are exactly in line and will remain so until further moved by the operator, and until platform 13 is entirely supported from craneway 16.

At this time movable trolley beams 15 can be released from the fixed trolley beams 14. The movable platform 13 is supported on movable trolley beams 15 which in turn are supported on rollers 29 (as shown in Fig. 2), which run on craneway 16. Platform 13 can be moved longitudinally by pulling on chain 73 until it reaches the point where the crane beams exactly match the next pair of fixed trolley beams under the next coke-drum.

The coke-drum 10 is now in line transversely with the movable trolley beams 15 and also with the fixed trolley beams 14 and is ready to be uncovered. The movable platform 13 is driven off

from the movable trolley beams 15 onto fixed trolley beams 14 under the coke-drum and thence under the lower cover 20 until the platform 13 has reached the desired limit. The rotating shafts 32 of retractable supports 31 are then lowered by rotating wheels 34 of each retractable support until platform 13 is locked in position.

The controls 67 are now set for the raising operation and the hydraulic jack 60 is actuated so that the platen 61 is raised and pressed against the lower cover 20 of the coke-drum. Bolts 64 are now placed in the holes in the bolting lugs 62 and 63 of the two members locking the lower cover 20 to the hydraulic jack 60. It is possible to exert 1,000 pounds more than the weight of the cover which will keep the cover in position without any other holding apparatus. The pneumatic wrench 52 is now set upon the circular track 50, and by actuating a lever arm 54, vertical movement is obtained which will raise the wrench 52 to engage the holding bolts 21 while the wrench is turned. The holding bolts 21 are next removed from the joint on the periphery of the manway which is covered by the lower cover 20. At this time the main body of the platform 13 is cleared and the operator retires behind the protective shield 70. By use of the window 71 in the shield, he is able to observe the movement of the lower cover 20 as hydraulic pressure is released by his operation of the controls 67 and at the same time is protected from the possible eruption of fluid and coke which may result when the seal is broken. Any released fluid and loose pieces of coke are carried through the open-grating floor of the platform 13 and dropped into a concrete trough 74, beneath the platform 13, from which they may be removed by pumps.

In some instances the cover 20 may resist loosening by the above procedure due to adhesion of the coke on the inside surface, or for other reasons. In such event, the controls 67 can be changed to effect a downward pumping action and the lower cover 20 can be literally pulled from contact with the lower manway of the coke-drum 10 when the hydraulic jack 60 is actuated. In this manner pressures as high as 27,000 pounds can be exerted, and this enormous pull can effect the complete lifting of the movable platform 13 from the trolley beams 14 unless prevented by the afore-mentioned locking ability of the four retractable supports or positioners 31 previously set.

After the lower cover 20 is loosened, all hydraulic pressure is removed from the jack 60 and the cover is lowered to a resetting position on guided column 65 supported on the movable platform. The supports 31 are retracted and the platform 13, now holding the cover 20, is moved transversely away from the coke-drum 10 onto the crane beams 15 and clear of the main structure 12. With the rails 75 now being clear, freight-car 27 can be moved directly under the lower manway and the coke-drum contents dropped therein. While the emptying process proceeds, the cover may be cleaned and made ready for reinstalling on the coke-drum.

After the contents of the coke-drum are deposited in the freight-car 27, the car is moved and the movable platform 13 is again positioned under the open manway as previously described. The controls 67 are set for the raising operation and the hydraulic jack 60 is actuated. The cover 20 is thus raised and forced against the manway periphery. The wrench 52 is replaced upon the track 50 and holding bolts 21 are set. The bolts 75

between the bolting lugs 62 and 63 of the cover 20 and the cover-holding platen 61 are next removed. The hydraulic shaft 76 is retracted, carrying with it the cover-holding platen 61. The supports 31 are next retracted, and the movable platform 13 and all its apparatus are moved onto the crane beams 15 ready for longitudinal movement to the next coke-drum 11 to be uncovered.

While a particular embodiment of the apparatus of the present invention has been described for the purpose of illustration, it should be understood that various modifications and adaptations thereof which will be obvious to one skilled in the art may be made without departing from the spirit of the invention.

Having thus described our invention we claim:

1. In a batch-type coking plant, comprising at least one coking vessel, a structure for supporting said vessel above grade, and a lower cover on said vessel, said cover being attached by means of peripheral holding bolts to the underside of said vessel, apparatus for removing said cover which includes: a pair of parallel trolley beams horizontally disposed under said vessel on opposite sides of said lower cover; a platform movably suspended from said trolley beams and adapted to be moved to or from a position under said cover on said beams; peripheral track means horizontally disposed on said platform, said track means being disposed under said holding bolts when said platform is positioned under said lower cover; wrench means movable on said track and adapted to remove said holding bolts from said cover; a vertical hydraulic jack positioned on said platform substantially concentric with said track means and adapted to lower or raise said cover; retractable supports on said platform adapted to exactly locate and assume the thrust or pull of said jack without substantially stressing said trolley beams; and a hydraulic pump and controls on said platform adapted to raise or lower said hydraulic jack.

2. In a batch-type coking plant, comprising at least one coking vessel, a structure for supporting said vessel above grade, and a lower cover on said vessel, said cover being attached by means of peripheral holding bolts to the underside of said vessel, apparatus for removing said cover which includes: a pair of parallel trolley beams horizontally disposed under said vessel on opposite sides of said lower cover; a platform movably suspended from said trolley beams and adapted to be moved to or from a position under said cover on said beams; peripheral track means horizontally disposed on said platform, said track means being disposed under said holding bolts when said platform is positioned under said lower cover; wrench means movable on said track and adapted to remove said holding bolts from said cover; a vertical hydraulic jack positioned on said platform substantially concentric with said track means and adapted to lower or raise said cover; retractable supports on said platform adapted to exactly locate and assume the thrust or pull of said jack without substantially stressing said trolley beams; hydraulic pump and controls on said platform adapted to raise or lower said hydraulic jack; and shielding means between said hydraulic means and controls and the region of said platform under said lower cover.

3. In a batch-type coking plant, comprising a plurality of coking vessels, a structure for supporting said vessels above grade, and a lower

cover on each of said vessels, said covers being attached by means of peripheral holding bolts to the underside of said vessels, apparatus for removing said covers which includes: a pair of parallel trolley beams horizontally disposed under each of said vessels on opposite sides of said lower covers; a craneway running alongside said lower covers and at right angles to and connecting each pair of said trolley beams; a pair of trolley beams movably suspended from said craneway and adapted to be moved into alignment with each pair of said trolley beams under said coking vessels; a platform movably suspended from said trolley beams and adapted to be moved to or from a position under each of said covers on said beams; peripheral track means horizontally disposed on said platform, said track means being disposed under said holding bolts when said platform is positioned under said lower covers; wrench means movable on said track and adapted to remove said holding bolts from said covers; a vertical hydraulic jack positioned on said platform substantially concentric with said track means and adapted to lower or raise said covers; retractable supports on said platform adapted to exactly locate and assume the thrust or pull of said jack without substantially stressing said trolley beams; and a hydraulic pump and controls on said platform adapted to raise or lower said hydraulic jack.

4. In a batch-type coking plant, comprising a plurality of coking vessels, a structure for supporting said vessels above grade, and a lower cover on each of said vessels, said covers being attached by means of peripheral holding bolts to the underside of said vessels, apparatus for removing said covers which includes: a pair of parallel trolley beams horizontally disposed under each of said vessels on opposite sides of said lower covers; a craneway running alongside said lower covers and at right angles to and connecting each pair of said trolley beams; a pair of trolley beams movably suspended from said craneway and adapted to be moved into alignment with each pair of said trolley beams under said coking vessels; a platform movably suspended from said trolley beams and adapted to be moved to or from a position under each of said covers on said beams; peripheral track means horizontally disposed on said platform, said track means being disposed under said holding bolts when said platform is positioned under said lower covers; wrench means movable on said track and adapted to remove said holding bolts from said covers; a vertical hydraulic jack positioned on said platform substantially concentric with said track means and adapted to lower or raise said covers; retractable supports on said platform adapted to exactly locate and assume the thrust or pull of said jack without substantially stressing said trolley beams; hydraulic pump and controls on said platform adapted to raise or lower said hydraulic jack; and shielding means between said hydraulic means and controls and the region of said platform under said lower cover.

5. In a batch-type coking plant, comprising at least one coking vessel, a structure for supporting said vessel above grade, and a lower cover on said vessel, said cover being attached by means of peripheral holding bolts to the underside of said vessel, apparatus for removing said cover which includes: a pair of parallel trolley beams horizontally disposed under said vessel on opposite sides of said lower cover; a platform

movably suspended from said trolley beams and adapted to be moved to or from a position under said cover on said beams; peripheral track means horizontally disposed on said platform, said track means being disposed under said holding bolts when said platform is positioned under said lower cover; wrench means movable on said track and adapted to remove said holding bolts from said cover; a vertical hydraulic jack; a platen fixed to said hydraulic jack, said jack and platen being positioned on said platform substantially concentric with said track means and adapted to lower or raise said cover; retractable supports on said platform adapted to exactly locate and assume the thrust or pull of said jack without substantially stressing said trolley beams; and a hydraulic pump and controls on said platform adapted to raise or lower said hydraulic jack.

6. In a batch-type coking plant, comprising at least one coking vessel, a structure for supporting said vessel above grade, and a lower cover on said vessel, said cover being attached by means of peripheral holding bolts to the underside of said vessel, apparatus for removing said cover which includes: a pair of parallel trolley beams horizontally disposed under said vessel on opposite sides of said lower cover; a platform movably suspended from said trolley beams and adapted to be moved to or from a position under said cover on said beams; peripheral track means horizontally disposed on said platform, said track means being disposed under said holding bolts when said platform is positioned under said lower cover; wrench means movable on said track and adapted to remove said holding bolts from said cover; a vertical hydraulic jack; a platen fixed to said hydraulic jack, said jack and platen being positioned on said platform substantially concentric with said track means and adapted to lower or raise said cover; retractable supports on said platform adapted to exactly locate and assume the thrust or pull of said jack without substantially stressing said trolley beams; hydraulic pump and controls on said platform adapted to raise or lower said hydraulic jack; and shielding means between said hydraulic means and controls and the region of said platform under said lower cover.

7. In a batch-type coking plant, comprising a plurality of coking vessels, a structure for supporting said vessels above grade, and a lower cover on each of said vessels, said covers being attached by means of peripheral holding bolts to the underside of said vessels, apparatus for removing said covers which includes: a pair of parallel trolley beams horizontally disposed under each of said vessels on opposite sides of said lower covers; a craneway running alongside said lower covers and at right angles to and connecting each pair of said trolley beams; a pair of trolley beams movably suspended from said craneway and adapted to be moved into alignment with each pair of said trolley beams under said coking vessels; a platform movably suspended from said trolley beams and adapted to be moved to or from a position under each of said covers on said beams; peripheral track means horizontally disposed on said platform, said track means being disposed under said holding bolts when said platform is positioned under said lower covers; wrench means movable on said track and adapted to remove said holding bolts from said covers; a vertical hydraulic jack; a platen fixed to said hydraulic jack, said jack and platen being

positioned on said platform substantially concentric with said track means and adapted to lower or raise said covers; retractable supports on said platform adapted to exactly locate and assume the thrust or pull of said jack without substantially stressing said trolley beams; and a hydraulic pump and controls on said platform adapted to raise or lower said hydraulic jack.

8. In a batch-type coking plant, comprising a plurality of coking vessels, a structure for supporting said vessels above grade, and a lower cover on each of said vessels, said covers being attached by means of peripheral holding bolts to the underside of said vessels, apparatus for removing said covers which includes: a pair of parallel trolley beams horizontally disposed under each of said vessels on opposite sides of said lower covers; a craneway running alongside said lower covers and at right angles to and connecting each pair of said trolley beams; a pair of trolley beams movably suspended from said craneway and adapted to be moved into alignment with each pair of said trolley beams under said coking vessels; a platform movably suspended from said trolley beams and adapted to be moved to or

25

from a position under each of said covers on said beams; peripheral track means horizontally disposed on said platform, said track means being disposed under said holding bolts when said platform is positioned under said lower covers; wrench means movable on said track and adapted to remove said holding bolts from said covers; a vertical hydraulic jack; a platen fixed to said hydraulic jack, said jack and platen being positioned on said platform substantially concentric with said track means and adapted to lower or raise said covers; retractable supports on said platform adapted to exactly locate and assume the thrust or pull of said jack without substantially stressing said trolley beams; hydraulic pump and controls on said platform adapted to raise or lower said hydraulic jack; and shielding means between said hydraulic means and controls and the region of said platform under said lower cover.
